UNITED STATES PATENT OFFICE.

FRANK J. BORKENSTEIN, OF FORT WAYNE, INDIANA, ASSIGNOR TO ART MOSAIC AND TILE COMPANY, OF TOLEDO, OHIO, A COPARTNERSHIP COMPOSED OF MICHAEL C. FIORITTO, RICHARD E. WRIGHT, AND FRANK J. BORKENSTEIN.

JOINT STRIP FOR CONCRETE FLOORS.

Application filed June 25, 1921. Serial No. 480,346.

To all whom it may concern:

Be it known that I, FRANK J. BORKENSTEIN, a citizen of the United States of America, and resident of Fort Wayne, in the county of Allen and State of Indiana, have invented certain new and useful Improvements in Joint Strips for Concrete Floors, of which the following is a specification.

This invention relates to improvements in joint strips for concrete floors especially those formed of strata, the superstratum of which is laid after the substratum has been partially hardened, it being the intention that the joint strip shall remain permanently in and become part of the floor. The object of the invention is to provide a strip so constructed that it may be set in the substratum of the floor while it is only partially hardened and so that a portion of the strip will project and be held in a vertical plane a fixed distance above the top surface of the substratum.

Another object of the invention is to so construct the strip that the parts of the superstratum of the floor that are separated by the strips will be protected by metal facings which abut one another.

And a further object of the invention is to provide a cushion between the portions of the superstratum that are separated by the strip so as to compensate for expansion and contraction of those portions without causing crumbling of their edges.

These objects are accomplished by the construction illustrated in the accompanying drawings in which:—

Fig. 1 is a perspective view of a strip embodying the invention;

Fig. 2 is a vertical section of a floor structure in which the strips are shown;

Fig. 3 is a perspective view showing the invention in a modified form and in which the cushion strip is included; and

Fig. 4 is a vertical section of a floor structure in which is shown the invention in the modified form.

The characters included in the description refer to parts shown on the drawings and designated thereon by corresponding characters:—

The strip is formed of sheet metal preferably of a non-corrosive character such as brass, the metal being of thin sheet or plate

stock. The strip has a central plane 1 at the upper edge of which is a contiguous L-shaped extension 2 and at the lower edge of the plane is a similar contiguous L-shaped extension 3, the extensions each having an outwardly projecting wing 4 and 5 respectively that lie in a common plane at right angles to the plane 1, the upper edge 6 and the lower edge 7 of the strip extending in corresponding planes parallel with that of the wings. Each wing has made therein a series of openings 8 and in the lower portion of the strip are made a series of notches 9.

In Fig. 3 is illustrated the invention in the modified form. In this instance, the angular extensions 16 and 17 that are contiguous respectively with the upper and lower edges of the plane 18 have corresponding wings 19 and 20 that project divergently downward and have notches 21 formed in their edges. Also, the lower edge of the strip 75 has a series of notches 22 as in the former instance. Included in this form is a cushion strip 23 that is permanently positioned in the fold between the plane 18 and the adjacent wall of the angular extension 16, the cushion being formed of a material capable of being compressed, such as spongy paper, brattice cloth or other suitable material.

In utilizing the invention, a substratum 10 of cement is first laid upon a permanent floor base 11 and leveled off in the customary manner and allowed to reach a partially set or hardened stage, at which time the strips are set in place by pressing the strips so that their lower edges 7 are projected 90 into the substratum 10 and so that the wings 4 and 5 come into contact with the upper surface 12 thereof. In thus positioning the strips, the substratum 10 becomes partially severed by the interposed lower edge of the strip, but not entirely because of the notches 9.

When the substratum 10 has matured to a further stage of hardness the superstratum 13 is laid upon the substratum and 100 covering the strips to the level of their upper edges 6. When the floor is thus completed and after it has hardened the surface of the superstratum is dressed by grinding or polishing in the customary manner, the upper 105 edges of the strips being also dressed by

the same finishing operation. Should the grinding or polishing operations, or the subsequent wear of the floor, result in the upper edges 6 of the strips being reduced so that 5 the extension 2 becomes severed from the plane 1, the portions 14 and 15 of the superstratum are nevertheless protected from crumbling at their adjacent edges because of their adherence to the angular extension 10 and the plane 1 respectively. In this manner, the severed portions of the flooring are rendered more durable and the life of the floor accordingly prolonged.

When the strip shown in Fig. 3 is employed 15 the notched edges of the wings 19 and 20 as well as the lower edge 24 of the strip are pressed into the substratum 25 of the floor while it is still "green," the superstratum 26 being subsequently applied and finished as 20 in the former instance. Joints formed in the superstratum by the strip in which the cushion strip 23 is included are rendered expansible owing to the presence of the compressible strip between the plane 18 and the 25 contiguous angular extension 16, and thus the edges of the superstratum at the joint

are rendered less liable to deterioration because of climatic conditions and wear.

What I claim is:—

1. A joint strip for concrete floors formed 30 with a central plane, there being along one edge thereof a contiguous L-shaped extension and at the opposite edge thereof a similar contiguous L-shaped extension, said extensions having corresponding wings that 35 project outwardly from the central plane, there being a series of apertures in each wing and in the lower edge of the strip.

2. A joint strip for concrete floors having a central plane and a folded angular ex- 40 tension contiguous with each of its edges, each extension having an outwardly projecting wing; and a cushion strip positioned in the fold between the central plane and the angular extension along its upper edge. 45

In testimony whereof I affix my signature, in presence of two witnesses.

FRANK J. BORKENSTEIN.
